UNITED STATES PATENT OFFICE.

HUGO W. FORSLUND, OF CHICAGO, ILLINOIS, ASSIGNOR TO J. W. REEDY ELEVATOR MANUFACTURING CO., OF CHICAGO, ILLINOIS, A CORPORATION OF ILLINOIS.

CONTROLLER-FRAME.

No. 917,858.

Specification of Letters Patent.

Patented April 13, 1909.

Application filed December 14, 1906. Serial No. 347,782.

To all whom it may concern:

Be it known that I, HUGO W. FORSLUND, a citizen of the United States, residing at Chicago, in the county of Cook and State of Illinois, have invented certain new and useful Improvements in Controller-Frames, of which the following is a full, clear, and exact specification.

This invention relates in general to electric hoisting machinery for elevators and the like, and more particularly to the controller frame, and the object of the same is to provide an improved means for securing the controller to the frame and for thoroughly insulating the controller therefrom.

A further object is to provide an improved construction of this character, which will be simple, cheap and strong, and efficient in operation.

To the attainment of these ends and the accomplishment of other new and useful objects, as will appear, the invention consists in the features of novelty in the construction, combination and arrangement of the several parts hereinafter more fully described and claimed, and shown in the accompanying drawings, illustrating an exemplification of the invention, and in which—

Figure 1 is an elevation of a portion of a machine constructed in accordance with the principles of this invention; Fig. 2 is an end elevation of a portion of the frame with the controller in position; Fig. 3 is a sectional view on line 3—3 of Fig. 1. Fig. 4 is a detail perspective view, partly in section, of a portion of the controller frame, and the clamp for securing the controller therein. Fig. 5 is a sectional view on line 5—5 of Fig. 1. Fig. 6 is a sectional view on line 6—6 of Fig. 2.

In the drawings, the same reference numerals designate similar parts throughout the several views.

In this exemplification of the invention, there is shown a portion of a frame 10 for suitable hoisting machinery, which may be secured in any desired manner to a ceiling or overhead support (not shown) so as to depend therefrom. This frame may be of any suitable size and width, and of any desired material, such as iron or the like, and so constructed as to form a space adjacent one end thereof constituting a controller space or frame.

The numerals 11—12 designate parallel

slates which are spaced from each other by 55 means of suitable frames 13, one preferably adjacent each end of the slates and are secured thereto in any desirable manner, preferably by means of screws or bolts 14 passing through the frames and into the adjacent 60 faces of the slates. These slates are of a size to fill the controller space of the main frame 10; that is, the edges of the slates rest against the walls of the space when placed therein, and the slates are so spaced from each other 65 that their outer faces will stand flush with faces of the frame 10.

Passing through the slates 11—12, preferably adjacent the end thereof and remote from the spacing frames 13, are rods or bars 70 15, which extend beyond the outer faces of the slates. Suitable clips or plates 16 are provided with apertures adjacent one edge thereof, through which the rods or bars 15 pass, and said apertures are preferably of a 75 diameter somewhat larger than the diameter of the rod or bar 15, to permit suitable insulating material 17 to be placed around the rod or bar 15, and within the aperture. When the slates are placed within the frame 80 10, the respective plates or clips 16 are placed against the face thereof and in contact with the face of the frame 10, and are securely clamped in position by means of nuts 18 engaging the ends of the rods or bars 85 15. If desired, and in order to prevent the nuts 18 contacting with the plates or clips 16, suitable insulating washers 18^a may be provided, as shown in Fig. 5.

The brushes 19, contacts 20, and magnetic 90 coils 21 are secured to the slate 11, and the operating mechanism or levers are secured to the slate 12, and are indicated generally by the reference numeral 22. A detail description of the brushes, coils and operating 95 levers or mechanism is not necessary, as they form no part of the present invention.

With this arrangement, it will be clearly seen that the controller is firmly secured to the frame and thoroughly insulated therefrom, and that when desired to remove the same all that is necessary is to loosen the nuts 18 so that the clips or plates 16 may be turned out of engagement with the frame 10, and both slates may be readily drawn 105 through one side of the frame.

Secured to the frame 10, preferably directly under the controller, is a motor frame

or saddle 23, which may be secured to the frame in any suitable manner, such as by means of screws or bolts 24, passing preferably through the bottom of the motor frame 5 or saddle 23, and into the frame 10, and insulating material 25 may be placed between the points of contact of the two frames, whereby they will be thoroughly insulated from each other. The edges of the flanges 10 26 (see Fig. 2) of the motor frame or saddle 23, are curved or formed on a perfect circle, and are adapted to receive or rest against the periphery of a motor case or frame 27 which is also formed on a perfect circle, and 15 said motor frame is held in position in any suitable manner, preferably by means of a bolt 28 passing through the motor saddle or frame, and into the motor frame.

Suitable conductors 29 serve as a means 20 for connecting the motor and controller.

For a clear understanding, this embodiment of the invention has been shown and specifically described, but

What I claim is:

25 1. In a device of the class described, the combination of a controller-frame, a controller, insulating supports for the controller, and means supported by the controller supports for removably clamping the supports 30 within the frame.

2. In a device of the class described, the combination of a controller frame, a controller, insulating supports for the controller comprising spaced slates, and means supported by the controller supports and engaging the faces of the slates and the frame for clamping the controller in the frame.

3. In a device of the class described, the combination of a controller frame, a controller, supports for the controller comprising spaced insulation members, means engaging the faces of the members and the frame for clamping the members in position, a connection between the clamping means, and means 45 for insulating the said connection from said first means.

4. In a device of the class described, the combination of a controller frame, a controller, supports for the controller comprising 50 spaced insulation members, clips engaging the faces of the members and the frame, and arranged opposite to each other, a rod passing through the members and the opposite pairs of clips, means engaging the ends of the 55 rods and the adjacent clip for clamping the members in position, and means for insulating the rod and the first said means from the clips.

5. In a device of the class described, the combination of a controller frame, a controller, insulation supports for the controller, a frame secured between the supports adjacent their ends for spacing the same, clamps comprising members engaging the face of the support and the controller frame, and an adjustable connecting member passing through the supports and the first members for drawing the said first members against the frame and supports, and means for insulating the clamps from the controller frame. 60 65 70

6. In a device of the class described, the combination of a controller-frame, a controller, spaced insulation supports for the controller, a bar passing through the supports and projecting beyond the outer face 75 thereof, clips engaging the frame and the outer face of the supports and provided with an aperture through which the rod passes, insulation within the aperture and surrounding the rod, and means engaging the ends of the 80 rod for clamping the clips in position.

7. In a device of the class described, the combination of a controller frame, a controller, spaced insulation supports for the controller, a bar passing through the supports, projecting beyond the outer face thereof and provided with a threaded extremity, clips engaging the frame and the outer face of the supports and provided with an aperture through which the ends of the rod pass, insulation within the aperture and surrounding 90 the rod and a nut engaging the end of the rod for clamping the clips in position.

8. In a device of the class described, the combination of a controller frame, a controller, spaced insulation supports for the controller, a bar passing through the supports, projecting beyond the outer face thereof and provided with a threaded extremity, clips engaging the frame and the outer face of 95 the supports and provided with an aperture through which the ends of the rod pass, insulation within the aperture and surrounding the rod, a nut engaging the end of the rod for clamping the clips in position, and insulation 100 disposed between the nut and the face of the clip.

In testimony whereof I have signed my name to this specification, in the presence of two subscribing witnesses, on this 12th day 110 of December A. D. 1906.

HUGO W. FORSLUND.
